UNITED STATES PATENT OFFICE.

JAMES A. FLOMERFELT, OF NEW YORK, N. Y.

DESIGN FOR A LINK CUFF-BUTTON.

SPECIFICATION forming part of Design No. 24,271, dated May 7, 1895.

Application filed April 13, 1895. Serial No. 545,667. Term of patent 14 years.

To all whom it may concern:

Be it known that I, JAMES A. FLOMERFELT, residing in the city, county, and State of New York, have invented a new and useful Design 5 for Link Cuff-Buttons, of which the following is a specification.

Reference is to be had to the accompanying drawings, illustrating my design, in which—

Figure 1 is a side elevation of a link cuff-10 button embodying the design, and Fig. 2 is a front view thereof.

My design consists in the substantially straight intermediate shank portion 1, of the button, as combined with, or viewed in con-

nection with, its angularly disposed heads 2, 15 3 at opposite ends of the shank, said heads leaning toward each other from the rear toward the front of the button, and as shown more particularly in Fig. 1 of the drawings.

What I claim is—

20 The design for a link cuff-button, substantially as herein shown and described.

In testimony whereof I affix my signature in the presence of two witnesses.

JAMES A. FLOMERFELT.

Witnesses:

CHAS. W. THOMPSON,
H. W. KRUMWIEDE.
